UNITED STATES PATENT OFFICE.

HUGO ECKENER, OF FRIEDRICHSHAFEN-ON-THE-BODENSEE, GERMANY, ASSIGNOR TO
LUFTSCHIFFBAU ZEPPELIN GESELLSCHAFT MIT BESCHRÄNKTER HAFTUNG, OF
FRIEDRICHSHAFEN-ON-THE-BODENSEE, GERMANY.

RIGID AIRSHIP WITH SEPARATE GAS CELLS.

Application filed November 27, 1922, Serial No. 603,603, and in Germany September 18, 1922.

My invention has reference to air ships, more particularly of the rigid type, with separate gas cells, and it particularly refers to means for preventing destruction of ships 5 of this kind by fire and lightning. The suggestions heretofore made for the utilization of a non-inflammable carrying gas for air ships were objectionable both on account of the comparative rarity and the resulting 10 high costs of production of such gases, and in view of the increased specific gravity which, for instance in the case of helium, is the double of hydrogen. Nor was it possible to arrive at practical results with the 15 suggestions heretofore made of providing the air ship with a jacket of nitrogen surrounding the gas cells because the loss of buoyancy incumbent thereon is excessive, aside from the complicated construction and 20 the high costs of a complete jacket of nitrogen or a non-combustible carrying gas.

My invention contemplates the utilization of non-inflammable carrying gases by providing non-inflammable gas of low specific 25 gravity such as helium only at such points of the ship which are particularly exposed to lightning strokes, especially the front or bow portion, and at the sections above the engines which are particularly liable to take 30 fire.

Strokes of lightning, as shown by experience, are liable to occur at the ends of the air ship only. At the rear end of the ship the widely projecting portions of the balancing and steering surfaces which are not filled 35 with gas, keep the lightning away from the gas in the hull so that at this point there is no obvious necessity of special protection by an incombustible gas. Such gas of 40 low specific gravity should accordingly be applied only at the bow and above the motor gondolas.

Means are also provided in the practice of my invention for the prevention of losses 45 of the expensive carrying gas caused by expansion due to the outer air pressure while the air ship rises or when the temperature of the gas increases. Such losses of gas can be prevented by a reinforcement of 50 the walls of the particular cells or compartments, thus rendering them capable of withstanding a higher pressure, and further by the provision of special expansion chambers into which the incombustible carrying gas is

allowed to escape when expanding. For 55 the same purpose means can be provided for removing part of the combustible carrying gas, such as hydrogen, filling the greater part of the ship, to such an extent that there will be sufficient room for the non-inflammable gas. The combustible carrying gas thus removed may preferably be used as 60 a fuel for the engine.

I may further reduce any additional sources of losses of the non-inflammable 65 carrying gas such as helium in the bow of the ship, by providing a fire-proof insertion or coating above the helium-filled cells with a view to preventing fluid metal which might be detached from the metal skeleton 70 of the air ship by melting in consequence of a stroke of lightning, from perforating the walls of the cells and allowing the gas to escape through the perforations.

Inasmuch as the special protective means 75 employed may be restricted to those sections of the air ship which is particularly exposed to danger, the additional weight resulting therefrom is so small that it does not appreciably interfere with the carrying capacity 80 of the air ship.

An airship embodying my invention is shown diagrammatically by way of example in the drawings annexed to this specification and forming part thereof.

Fig. 1 is a longitudinal section, while 85 Fig. 2 illustrates the bow of the ship on a somewhat enlarged scale.

In the drawing an air ship of the rigid type is shown with the outer envelop *a* surrounding the skeleton hull (not shown). The cells *b* are filled with hydrogen gas, while the cells *c* at the bow of the ship for about a quarter up to about one-fifth of the length of the ship are filled with an incombustible gas of low specific gravity, such as helium. The motor gondolas are indicated at *d*. Above these gondolas separate small helium cells *e* are arranged, and similar separate helium cells may also be provided above the passenger-cabins. In the modification shown in Figure 2 the helium cells *c* are provided with a protective coating *f*. The three helium cells *c* communicate by way of openings *h* with a collapsible cell *g* mounted in the interior of the hydrogen cell *b*.

My invention has been described with ref-

erence to its principal features without limiting it to the particular forms of embodiment herein shown and described, for alterations and modifications of such embodiments may 5 occur within the spirit of my invention as the conditions of utilization will direct, and without limiting the scope of the invention thereby.

I claim:—

- 10 1. An airship comprising a cell filled with a non-inflammable carrying gas, another cell filled with inflammable gas, a collapsible cell within said latter cell communicating with said former cell and means connected with said former cell and means connected with 15 said latter cell for allowing the escape of inflammable gas therefrom.

2. An airship comprising a motor gondola, a cell filled with a non-inflammable carrying gas, another cell filled with inflammable gas, a collapsible cell within said latter cell 20 communicating with said former cell and a communication between said latter cell and the motor gondola.

3. An airship comprising a plurality of gas cells, a bow cell being filled with a non-inflammable carrying gas, other cells with an inflammable gas, the walls of said bow cell being stronger than those of the other cells. 25

In testimony whereof I affix my signature. 30

HUGO ECKENER.
